DESIGN FOR A TOY

Edward McCandlish, Ypsilanti, Mich.

Application January 2, 1936, Serial No. 60,400

Term of patent 7 years

To all whom it may concern:

Be it known that I, Edward McCandlish, a citizen of the United States, residing at Ypsilanti, in the county of Washtenaw and State of Michigan, have invented a new, original, and ornamental Design for a Toy, of which the following is a specification, reference being had to the accompanying drawing, forming part thereof.

Fig. 1 is a side view of a toy showing my new design,

Fig. 2 is a top view, partly in perspective, and
Fig. 3 is a front perspective view thereof.

I claim:

The ornamental design for a toy, as shown.

EDWARD McCANDLISH.
